HAND BRAKE MECHANISM

Joseph Kuchar, Chicago, Ill., assignor, by mesne assignments, to Union Railway Equipment Company, Chicago, Ill., a corporation of Illinois

Filed June 13, 1962, Ser. No. 202,259

9 Claims. (Cl. 74—503)

My present invention relates generally to hand brakes for railway cars and more particularly to the operating or control mechanism therefor.

Specifically, the invention is concerned with a manually operated brake mechanism of the non-spin type. In the older forms of hand brakes, release thereof required a slight rotation of the hand wheel in a winding or brake setting direction to permit release of the holding pawl, after which the hand wheel was allowed to spin to release the brakes. This arrangement was a frequent source of injury to the brakeman and solutions of the problem took the form of the so-called non-spin hand brake in which no or a very slight movement of the handwheel was necessary to effect release.

Generally speaking, non-spin brakes are divided into two classes, viz., one in which the pinion and gear are always in mesh and spinning of the handwheel was prevented by some form of clutch, while the other included a means for relatively moving the pinion and gear out of mesh. The former constitutes a costly structure and considerable difficulty was encountered with the latter in overcoming the friction between the pinion and gear teeth due to the pull of the set brakes.

It is therefore the principal object of my present invention to provide a non-spin hand brake wherein the brakes are released by moving the pinion out of mesh with the gear through a compound leverage action that materially lessens the effort required for this separation.

A further object of my present invention is to provide a mechanism of the character indicated wherein the compound leverage is effected by the coaction of an eccentric with one end of a lever pinion carrier.

Now in order to acquaint those skilled in the art with the manner of constructing and utilizing devices in accordance with the principles of my present invention, I shall describe in connection with the accompanying drawings, a preferred embodiment of my invention.

In the drawings:

FIGURE 1 is a front elevational view of my improved mechanism, looking in the direction indicated by the arrow 1 in FIGURE 2, with the hand wheel being omitted and with the forward wall of the housing being broken away to show the pinion carrier assembly which is positioned for the winding operation of the mechanism;

FIGURE 2 is a vertical sectional view, taken substantially along the line 2—2 in FIGURE 1, looking in the direction indicated by the arrows;

FIGURE 3 is a fragmentary view similar to FIGURE 1, but showing the carrier assembly pivoted upwardly to a position disengaging the pinion from the gear to permit the unwinding operation of the mechanism;

FIGURE 4 is a fragmentary vertical sectional view, taken substantially along the line 4—4 in FIGURE 2, looking in the direction indicated by the arrows;

FIGURE 5 is a fragmentary vertical sectional view, taken substantially along the line 5—5 in FIGURE 1, looking in the direction indicated by the arrows; and

FIGURE 6 is a fragmentary vertical sectional view, taken substantially along the line 6—6 in FIGURE 1, looking in the direction indicated by the arrows.

Referring now to FIGURES 1 and 2, the numeral 10 designates the usual brake chain whose ends are respectively connected in the usual manner to the braking system of a railway car (not shown) and to a pin 11 that is

2

mounted in and extends laterally from the reinforced web of a spur gear 12. The gear 12 is journaled on a shaft 13 whose ends are respectively supported in the front and rear walls 14 and 15 of an enclosing housing 16; the wall 15 includes a plurality of apertured lugs 17 for receiving bolts to secure the housing 16 to the end wall of the car body 18. Also journaled on the shaft 13 is a winding drum 19 whose periphery is appropriately grooved to receive alternate links of the brake chain 10 during the winding operation as hereinafter described.

In the winding position shown in FIGURES 1 and 2, the gear 12 meshes with a pinion 20 that may be integrally formed with an operating shaft 21 which extends outwardly of the housing 16 through a vertically elongated opening 22 provided in the front wall 14. The outer end of the shaft 21 has secured thereto a vertical hand wheel 23, and, within the housing 16, the shaft 21 is journaled in a pair of laterally spaced, identical plates 24. To prevent foreign material from entering the opening 22, an annular pinion seal 21a is disposed about the operating shaft 21 intermediate of the front housing wall 14 and the forward plate 24. In the arrangement shown, each plate 24 is generally pentagonal in shape although the latter is not of the essence. The plates 24 are secured together to form a rigid assembly by means of a plurality of appropriately located rivets 25, three in number being shown, with each rivet being bridged between the plates 24 and enclosed therebetween by a sleeve 26 to maintain the spacing of the plates 24. For a purpose to be presently explained, one of the rivets 25 is positioned generally above the shaft 21.

The plates 24 and the immediately associated parts, including the shaft 21, rivets 25 and sleeves 26, constitute a pinion carrier assembly which is indicated generally by the reference numeral 27. The assembly 27 is journaled on a sleeve 28 (see FIGURE 6) for vertical rocking or pivotal movement toward and away from the gear 12. The sleeve 28 extends transversely through the plates 24 and is supported on a machine screw 29 whose ends respectively bridge the front and rear housing walls 14 and 15, or pivotal movement toward and away from the gear 12. The sleeve 28 extends transversely through the plates 24 and is supported on a machine screw 29 whose ends respectively bridge the front and rear housing walls 14 and 15. As shown in FIGURE 1, the screw 29 is located to the right of the vertical center line of the shaft 21 and, with respect to the assembly 27, is positioned at the right end thereof.

At the left end of the carrier assembly 27, each plate 24 is formed with an open end slot 30; the slots 30 being in registration with each other. Operably related to the walls of the slots 30 are spaced, eccentric cams 31 (see FIGURES 1, 4 and 5) which have lobe portions 32 and 55 which may be integrally formed with a release shaft 33. The ends of the shaft 33 are respectively journaled in the front and rear housing walls 14 and 15, and the left end of the shaft 33, as viewed in FIGURE 5, extends outwardly of the wall 14 and has secured thereon a release handle 34. Forwardly projecting horizontal stop pins 35 and 36, which may be integrally formed with the front housing wall 14, are provided for limiting pivotal movement of the lever 34 and for facilitating quick location of the latter in either one of its two operative positions.

Also carried by the operating shaft 21, or integrally formed therewith as desired, is a ratchet wheel 37 which is constantly engaged by a pawl 38 that is journaled on the spacer sleeve 26 which lies above the shaft 21 (see FIGURES 1 and 2). The pawl 38 is weighted at 39 to constantly gravity bias the same in engagement with the ratchet wheel 37. From the foregoing, it will be un-

derstood that the pinion 20 and ratchet wheel 37 are rigidly related with respect to each other by reason of their being integral with the shaft 21 and hence rotate together whenever the shaft 21 is rotated and also simultaneously move upward and downward whenever the carrier assembly 27 is pivoted.

When the parts occupy the several positions shown in FIGURE 1, the mechanism is conditioned for winding to set the brakes. In particular, the release handle 34 occupies a position in abutment with the stop pin 35, and serves to locate the eccentric cam lobes 32 in their downward positions. To prevent movement of the release handle 34 due to impact and to maximize the service life of the release mechanism, the high points of the cam lobes 32 in the operative position shown are arranged to lie out of coincidence with the vertical plane passing through the axis of the cams 31, on the same side of this plane as the pivot sleeve 28 of the pinion carrier assembly 27, and at an angle A, preferably of 20°, from the plane.

Concurrently, the carrier assembly 27 is located in its lower position wherein the pinion 20 meshes with the gear 12. The hand wheel 23 may then be rotated to wind the chain 10 around the drum 19 to set the brakes. During this operation, the pawl 33 wipes over the teeth of the ratchet wheel 37 and prevents unwinding of the chain 10 while the brakeman shifts his grip on the hand wheel 23.

To release the brakes, the handle 34 is swung to the position shown in FIG. 3, in abutment with the stop pin 35, to thereby rotate the cam lobes 32 to the upward position indicated in the same figure. This action rocks the carrier assembly 27 upwardly and separates the pinion 20 from the gear 12 to permit the drum 19 to unwind without spinning of the hand wheel 23. During the lifting movement of the carrier assembly 27, rotation of the gear 12 is additionally prevented by the interaction of the ratchet wheel 37 and pawl 33 until the pinion and gear teeth are entirely free of each other. Upward movement of the operating shaft 21 is permitted by the elongated opening 22 in the housing front wall 14.

An important feature of the invention is the mechanical advantage afforded by the coaction of the release handle 34 and cams 31 with the carrier assembly 27 in overcoming the friction between the teeth of the pinion and gear. When the brakes are fully set, this friction is of a high order and considerable difficulty has been encountered with preceding devices in solving this problem except with expensive designs.

In the structure shown, an economical and mechanically feasible solution has been provided by employing a compound leverage mechanism for securing the separation of the pinion and gear. It will be apparent that the assembly 27, which serves as a support for the pinion 20, is a lever whose fulcrum is the sleeve 28 positioned at one end of the assembly and which includes one arm whose length is the distance between the shaft 21 and sleeve 28, and another and longer arm whose length is the distance between the sleeve 28 and the eccentric cams 31. The second lever in the mechanism is composed of the relatively short arms provided by the cam lobes 32 and the relatively longer arm provided by the release handle 34 with the fulcrum furnished by the release shaft 33 that is journaled in the housing 16. The cumulative action of these levers provides a highly effective and structurally simple means for overcoming tooth friction as the pinion is drawn away from the gear.

To condition the mechanism for brake setting, the release handle 34 is swung back to the position shown in FIGURE 1, in abutment with the stop pin 35, which remeshes the pinion 20 with the gear 12. Slight rotation of the handwheel 23 may be necessary to secure tooth engagement.

While I have shown and described what I consider to be a preferred embodiment of my present invention, it will be understood that various modifications and rearrangements may be made therein without departing from the spirit and scope of my invention.

I claim:

1. Hand brake mechanism comprising a winding drum, a gear having means for winding a brake chain around said drum when said gear is rotated, a carrier assembly including a pair of spaced plates secured together and pivoted at adjacent ends thereof for rocking as a unit, an operating shaft bridged between and journaled in said plates, a pinion secured to said shaft in mesh with and operable to rotate said gear in a winding direction, and means coacting with the ends of said plates remote from the pivot thereof to rock said assembly and disengage said pinion from said gear to permit unwinding of said drum.

2. For use in a hand brake mechanism, the combination of a rotatable gear, a carrier assembly including a pair of spaced plates secured together and pivoted at adjacent ends thereof for rocking as a unit, an operating shaft bridged between and journaled in said plates, a pinion secured to said shaft in mesh with and operable to rotate said gear in one direction, and lever means coacting with the ends of said plates remote from the pivot thereof for rocking said assembly to disengage said pinion from said gear whereby to permit rotation of the latter in the other direction.

3. For use in a hand brake mechanism having a housing, a winding drum, and a gear having means for winding a brake chain around the drum when the gear is rotated, the combination of a pinion carrier assembly including a pair of spaced plates secured together and pivoted at adjacent ends thereof within and on the housing for rocking as a unit, the ends of said plates remote from the pivot including registering slots, and operating shaft bridged between and journaled in said plates and extending outwardly of the housing for association with a handwheel, a pinion secured to said shaft in mesh with and operable to rotate the gear in a winding direction, and cam means journaled in the housing and rotatably engageable with the walls of said slots to rock said assembly in a direction disengaging said pinion from the gear.

4. For use in a hand brake mechanism, the combination of a rotatable gear, a carrier assembly including a pair of spaced plates secured together and pivoted at adjacent ends thereof for rocking as a unit, an operating shaft bridged between and journaled in said plates, a pinion secured to said shaft in mesh with and operable to rotate said gear in one direction, a ratchet wheel secured to said shaft, a pawl biased to a position engaging said ratchet wheel to prevent rotation of said gear in the other direction while said pinion and gear are in mesh, and means coacting with the ends of said plates remote from the pivot thereof to rock said assembly and disengage said pinion from said gear whereby to permit rotation of the latter in the other direction.

5. Hand brake mechanism comprises a housing, a winding drum, a gear having means for winding a brake chain around said drum when said gear is rotated, a carrier assembly including a pair of spaced plates secured together and pivoted at adjacent ends thereof within and on said housing for rocking as a unit, the ends of said plates remote from the pivot including registering slots, an operating shaft bridged between and journaled in said plates and extending outwardly of said housing, a pinion secured to said shaft in mesh with and operable to rotate said gear in a winding direction, a ratchet wheel secured to said shaft, a pawl biased to a position engaging said ratchet wheel to prevent an unwinding rotation of said gear while said pinion and gear are in mesh, and cam means journaled in said housing and rotatably engageable with the walls of said slots for rocking said assembly

in a direction disengaging said pinion from said gear.

6. For use in a hand brake mechanism having a housing, a winding drum, and a gear having means for winding a brake chain around the drum when the gear is rotated, the combination of a pinion carrier assembly including a pair of spaced vertical plates secured together and pivoted at adjacent ends thereof within and on the housing for rocking as a unit about a horizontal axis, the ends of said plates remote from the pivot including registering slots, a horizontal operating shaft bridged between and journaled in said plates and extending outwardly of the housing, a pinion secured to said shaft in mesh with and operable to rotate the gear in a winding direction, cam means journaled in the housing about a horizontal axis and engageable with the walls of said slots, said cam means having lobes extending downwardly in one operative position with the high points lying out of coincidence with the vertical plane passing through the axis of said cam means on the same side of the plane as the pivot of said plates, and means for rotating said cam means to a second operative position whereupon engagement of said cam lobes with said slots serves to rock said assembly in a direction disengaging said pinion from the gear.

7. For use in a hand brake mechanism having a housing, a winding drum, and a gear having means for winding a brake chain around the drum when the gear is rotated, the combination of a pinion carrier assembly including a pair of spaced vertical plates secured together and pivoted at adjacent ends thereof within and on the housing for rocking as a unit about a horizontal axis, the ends of said plates remote from the pivot including registering slots, a horizontal operating shaft bridged between and journaled in said plates and extending outwardly of the housing, a pinion secured to said shaft in mesh with and operable to rotate the gear in a winding direction, cam means journaled in the housing about a horizontal axis and engageable with the walls of said slots, a release handle for rotating said cam means between two operative positions, said cam means having lobes extending downwardly in one operative position with the high points lying out of coincidence with the vertical plane passing through the axis of said cam means on the same side of the plane as the pivot of said plates, said cam means upon rotation to its second operative position serving to rock said assembly in a direction disengaging said pinion from the gear, and stop means associated with said release handle and serving to locate the latter in two positions corresponding to the two operative positions of said cam means.

8. For use in a hand brake mechanism, the combination of a rotatable gear, a carrier assembly pivoted at one end for rocking movement, an operating shaft journaled in said carrier assembly, a pinion secured to said shaft in mesh with and operable to rotate said gear in one direction, a ratchet wheel secured to said shaft, a pawl biased to a position engaging said ratchet wheel to prevent rotation of said gear in the other direction while said pinion and gear are in mesh, and means coacting with the end 5 of said carrier assembly remote from the pivot thereof to rock said assembly and disengage said pinion from said gear whereby to permit rotation of the latter in the other direction.
9. For use in a hand brake mechanism having a housing, a winding drum, and a gear having means for winding a brake chain around the drum when the gear is rotated, the combination of a pinion carrier assembly including at least one vertical plate pivoted at one end thereof within and on the housing for rocking movement 15 about a horizontal axis, the end of said plate remote from the pivot including a slot, a horizontal operating shaft journaled in said carrier assembly and extending outwardly of the housing, a pinion secured to said shaft in mesh with and operable to rotate the gear in a winding direction, cam means in the housing journaled about a horizontal axis and engageable with the walls of said slot, said cam means having at least one lobe extending downwardly in one operative position with the high point lying out of coincidence with the vertical plane passing 20 through the axis of said cam means on the same side of the plane as the pivot of said plate, and means for rotating said cam means whereby to move the high point of said cam lobe through the said vertical plane to a second operative position on the opposite side of the plane as the pivot of said plate whereupon engagement of said cam lobe with said slot serves to rock said assembly in a direction disengaging said pinion from the gear.
